STRAND TWISTING DEVICE

Axel C. Nystrom, Rutherford, and Walter J. Volckhausen, Teaneck, N. J., assignors to Western Electric Company, Incorporated, New York, N. Y., a corporation of New York

Original application November 4, 1947; Serial No. 783,874. Divided and this application June 30, 1948, Serial No. 36,096

5 Claims. (Cl. 57—59)

1

This is a division of a copending application of Axel C. Nystrom and Walter J. Volckhausen, Serial No. 783,874, filed November 4, 1947 now Patent Number 2,471,973.

The invention herein relates to material supplying apparatus, and more particularly to an apparatus for supplying tape-like cores to stranding machines for forming switchboard cables.

In the manufacture of switchboard cables, it has been found desirable to produce the cables with flat or oval cross-sectional contours as they may be more readily disposed in the compact areas in switchboard equipment. The insulated electrical conductors of cable of this type are formed about a tape-like material more commonly known as pressboard which may be of various widths depending upon the size of cable to be formed thereon, and more particularly to the number of electrical conductors to be wound spirally thereabout.

An object of the invention is to provide a material supplying apparatus which is simple in structure, efficient in operation, readily adjustable for various sizes of material supplies and easily actuatable for the mounting of the material supplies therein.

With this and other objects in view, the invention comprises a material supplying apparatus including a frame with space aligned apertured members to removably receive an element which is to support a supply of material for rotation between the members as the material is withdrawn from the supply. Latches are carried by the frame and disposed adjacent the ends of the element for selective actuation thereof to free the element for removal in either direction from the apertured members.

More specifically the invention includes a frame in the form of a flyer rotated about its axis to rotate a supply pad of tape-like material about the centerline of a path along which the material is advanced longitudinally. The supply pad of material is supported on a spindle held in place by latches, at the ends thereof, movable against the forces of springs whereby the spindle may be removed from the frame, or apertured members carried thereby, at either side of the frame. Apertured retaining elements, which are the immediate supports for the spindle, are positioned upon each side of the pad of material concentric with the spindle. They include externally threaded members movable in internally threaded members, varied distances depending upon the width of the pad of material to engage opposite sides thereof. Individual latches are

2

provided to hold the retaining elements in their adjusted positions.

Other objects and advantages will be apparent from the following detailed description when considered in conjunction with the accompanying drawings, wherein

Fig. 1 is a front elevational view of the material supplying apparatus, and

Fig. 2 is an enlarged fragmentary sectional view of the material supporting mechanism of the apparatus.

The material supplying apparatus includes a flyer unit indicated generally at 10 rotatable in bearings 11 and 12 supported by mounting brackets 14 and 15. The flyer 10 is in the form of a frame composed of channel members 18 disposed at spaced positions parallel with each other and connected to enlarged head-like portions of shafts 19 and 20 at their ends. The shafts 19 and 20 are journaled in alignment with each other in the bearings 11 and 12. Sleeves 21 and 22 are mounted in aligned apertures 23 and 24 of the channel members 18 to receive annular internally threaded members 25 and 26. The sleeves 21 and 22 and the members 25 and 26 are fixed parts of the frame or channel members 18.

Adjustable retaining elements 27 and 28 are externally threaded to be received in their internally threaded members 25 and 26 respectively, and are internally apertured as at 29 and 30 to receive a tubular supporting element or spindle 31. Handles 32 are mounted in the ends of the supporting element 31 whereby the element may be readily removed from the apertures 29 and 30 from either side of the machine. Latches 33 and 34 slide longitudinally in guideways 35 and 36 are normally held in the position shown in Fig. 2 adjacent their respective ends of the supporting element 31 by the force of their respective springs 39 and 40. The springs 39 and 40 are disposed concentric with rods 41 and 42 movable longitudinally in apertured lugs 43 and 44 carried by brackets 45 and 46 which are supported by the channel members 18. The springs 39 and 40 abut their respective lugs 43 and 44 at like ends, their opposite ends engaging outwardly extending handles 47 and 48 which are fixed to the latches 33 and 34, respectively. By moving the handles 47 and 48 to the left (Fig. 3) their respective latches 33 and 34 will be moved away from the ends of the element 31 freeing it to be removed from the apertures 29 and 30.

The retaining elements 27 and 28 have grooves 49 and 50 therein disposed at spaced positions 55 about their peripheries to receive retaining

latches 53 and 54 respectively. The latches 53 and 54 are mounted on the inner ends of rods 55 and 56 which extend through apertures in the brackets 45 and 46. Handles 57 and 58 are mounted on the outer ends of the rods 55 and 56 for use in moving the latches 53 and 54 outwardly free of any of the grooves 49 and 50 where they are held normally by the forces of springs 59 and 60. Aligning pins 61 and 62 carried by the brackets 45 and 46 and entering apertures 63 and 64 in the handles 57 and 58 respectively, hold the latches 53 and 54 against rotation. The pins 61 and 62 serve also to hold the latches 53 and 54 disengaged when the handles are rotated after they are moved outwardly free of the pins. Laterally extending rods or fingers 67 and 68 are carried by the retaining members 27 and 28 to lie adjacent the sides of a pad or supply of material 70.

The shaft 20 carries guide elements 15 to guide the material 76 from the supply pad 70 into a narrow opening through the shaft wherein the material is guided in a path coincident with the axis of rotation of the flyer unit or frame 10 during longitudinal advancement of the material. A sprocket 77 mounted on the shaft 20 is connected to a sprocket 78 of a drive shaft 79 by a chain 80. The drive shaft 79 is supported in suitable bearings 81 and driven by a motor 82 through a sprocket and chain connection 83. In the present embodiment of the invention, the motor 82 is in a circuit 85 with a control switch 86. In actual structure, the necessary relays (not shown) are provided together with the conventional start switch 87 and stop switch 88. The switch 86 is normally closed and will be actuated into open position by a lever 90, pivotally supported at 91 on a bracket 92 which in turn supports a switch 86, when the pad 70 becomes empty.

During operation of the apparatus, let it be assumed that a full pad of material 70 is mounted in the frame of the flyer 10 and this material is threaded through the shaft 20 and directed to the means (not shown) which causes its longitudinal advancement. While the material 76 is advanced longitudinally through the shaft 20, it is rotated about its longitudinal centerline by rotation of the flyer 10. This is brought about by the operation of the start switch 87 to energize the motor 82 to drive the shaft 79 which in turn will drive the flyer 10. This operation continues until the pad 70 becomes empty or approximately empty at which time the lever 90 is rocked clockwise until the switch 86 is actuated into open position, thus deenergizing the motor 82. The stop switch 88 is then actuated.

The operator then actuates the closest latch 33 or 34 to free the element 31 for removal whereby a core, which usually constitutes the central portion of the pad 70, may be removed and a new pad of material 70 installed in the flyer. The new pad of material is installed by holding the pad in a position between the retaining elements 28 with its core aligned with the element 31 after which the element may be forced through the core of the pad until it comes to a stop against the latch 33 or 34 which has not been actuated at this time. In actual practice, the element 31 may not be removed entirely from the adjacent retaining element 27 or 28 and in this manner the latch which has been actuated to free the element 31 will be held in its open position resting against the periphery of the element. After the pad has been located

centrally of the element 31 the operator need only force the element 31 inwardly against the latch 33 or 34 which has remained closed and the remaining latch which has been actuated will automatically move into place by the force of its spring 39 or 40.

If it is desirable to install a pad of different width, this may be accomplished by moving the latch 53 outwardly against the force of its spring 59 through the aid of the handle 57. In this instance the aligning pin 61 may function as a hold means to hold the latch 53 in its outer position after the handle 57 has been moved free of the pin and rotated a given distance to rest on the outer end of the pin. When this has been accomplished, the retaining element 27 may be rotated in either direction depending upon whether a wider or narrower pad is to be installed. The grooves 49 are conveniently positioned whereby one of them may be brought into registration with the latch 53 at the end of any of the adjustments of the retaining element 27. At this time, the latch 53 will be forced into the selected groove 49 by the force of its spring 59 merely by rocking the latch until the pin registers with the aperture 63 in the handle 57. In a similar manner the retaining element 28 may be adjusted. These adjustments are only made when it is desirable to modify the apparatus for forming a different size cable. If the apparatus is set up to form a cable of a given size, pads 70 of the same width will be successively mounted in the flyer and the leading end of a new pad will be connected to the following end of a previously empty pad whereby the continuous formation of a cable may result.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A material supplying apparatus comprising a frame, spaced aligned apertured members carried by the frame, an element removably disposed in the apertured members to support a supply of material for rotation between the apertured members as the material is withdrawn from the supply, and latches carried by the frame and disposed adjacent the ends of the element for selective actuation to free the element for removal in either direction from the apertured members.

2. A material supplying apparatus comprising a frame, spaced aligned apertured members carried by the frame, an element removably disposed in the apertured members to support a supply of material for rotation between the apertured members as the material is withdrawn from the supply, latches carried by the frame and disposed adjacent the ends of the element for selective actuation to free the element for removal in either direction from the apertured members, and means whereby the said apertured members may be moved relative to each other and the frame to retain the supply of material at a given position relative to the frame.

3. A material supplying apparatus for supporting a pad of tape-like material and rotating the material about an axis coincident with the longitudinal centerline of the material pulled from the pad, the apparatus comprising a rotat-

able frame having spaced members, apertured retaining elements carried by the frame members, a spindle removably disposed in the apertured retaining elements to rotatably support the pad of material, and spring pressed latches normally engaging their respective ends of the spindle to hold the spindle in the apertured elements and selectively actuatable to free the spindle for removal from either side of the apertured elements.

4. A material supplying apparatus for supporting a pad of tape-like material and rotating the material about an axis coincident with the longitudinal centerline of the material pulled from the pad, the apparatus comprising a rotatable frame having spaced members, aligned internally threaded members carried by the frame members, externally threaded apertured retaining elements mounted in their respective internally threaded members for adjustment of the elements toward and away from each other by relative rotation of the elements and members to singly locate pads of various sizes centrally of the said path, a spindle removably disposed in the apertures of the retaining element to support the pad, and means to removably secure the spindle in place.

5. A material supplying apparatus for supporting a pad of tape-like material and rotating the material about an axis coincident with the longitudinal centerline of the material pulled from the pad, the apparatus comprising a rotatable frame having spaced members, aligned internally threaded members carried by the frame members, externally threaded apertured retaining elements mounted in their respective internally threaded members for adjustment of the elements toward and away from each other by relative rotation of the elements and members to singly locate pads of various sizes centrally of the said path, the elements having spaced grooves therein, latches to selectively enter any of the grooves of their respective elements to lock the elements in their adjusted positions, a spindle removably disposed in the apertures of the retaining element to support the pad, and means to removably secure the spindle in place.
